UNITED STATES PATENT OFFICE.

SAMUEL LOYD, OF BROOKLYN, NEW YORK.

PUZZLE DEVICE.

Application filed April 4, 1923. Serial No. 629,772.

To all whom it may concern:

Be it known that I, SAMUEL LOYD, a citizen of the United States, and a resident of the borough of Brooklyn, county of 5 Kings, and State of New York, have invented certain new and useful Improvements in Puzzle Devices, of which the following is a specification.

This invention relates to improvements in 10 puzzle device.

One of the objects of this invention is to produce a puzzle device in which a number or symbol embodied in one or a series of panels or tables hereinafter called "tabulated symbols" or "tabulated numbers" will be exposed simultaneously with one or a series of numbers or symbols, each of which designates an individual panel or table and which will hereinafter be called "index symbols" or "index numbers."

Another object of this invention is to produce a device in which a series of such tables or panels, each identified by an index number, and composed of a series of tabulated numbers identified with such index numbers are suitably exposed on one member and preferably on a facing member, and a disc carrying two series of numbers, one of which is identified with the tabulated numbers and the other with the index numbers, is rotatably associated with two openings, preferably in said facing member, and is, upon rotation, adapted to expose through one of such openings one or a series of index numbers and through the other of such openings a tabulated number that appears in one or a series of such tables indicated by the index numbers.

Another object of my invention is to arrange such tabulated and index numbers on 40 a disc in concentric rows, one of such rows preferably having its numbers inverted in relation to the other row and said numbers also preferably being arranged with the tabulated number and its index number or numbers in diametric and aligned opposition thereto.

Another object of this invention is to produce a device in which the tabulated number exposed in one of such openings shall comprise one of a table of numeric permutations and the index numbers shall constitute indices of such numeric permutations.

With these and other objects in view, the 55 invention comprises the combination of

members and arrangement of parts so combined as to co-act and cooperate with each other in the performance of the functions and the accomplishment of the results herein contemplated, and comprises in one of its 60 adaptations the species or preferred form illustrated in the accompanying drawings, in which:—

Fig. 1 is a plan view of a puzzle device embodying my invention; 65

Fig. 2 is a rear view of the device shown in Fig. 1;

Fig. 3 is a section on the line 3—3 of Fig. 2;

Fig. 4 is a plan view of the disc dis- 70 mounted from the other parts of the device;

Fig. 5 is a diagrammatic view of a pocket form of my improved puzzle device; and

Fig. 6 is a vertical section on the line 75 6—6 of Fig. 5.

Referring now to these drawings, and particularly to Figs. 1 to 4 thereof, which illustrate a preferred embodiment of my invention, A indicates a facing member having as illustrated inscribed on its outer face a series of six tables or panels B—C—D—E—F and G respectively, each of which panels is individually identified by an index symbol or number, and in the embodiment 80 shown I have employed indices from 1 to 6 respectively. Each panel or table contains in column formation a series of numbers or other symbols which I shall term tabulated symbols or numbers, each of which tabulated 85 numbers are suitably identified with the index number and preferably comprising permutations of the various combinations of index numbers or indices. Said facing member A may be made as ornamental as desired 90 and is, as illustrated, provided with two spaced openings or apertures H—I, through one of which an index symbol or number or series of such symbols or numbers or like indicia is adapted to be exposed, and 100 through the other of which a tabulated symbol or number identified with such index symbol or number or series of symbols or numbers, and said tabulated number so exposed preferably comprising a permutation of one or a combination of such index numbers, is adapted to be exposed simultaneously.

In the embodiment shown, the age of a person may be disclosed simultaneously with 110

an index number or combination of such index numbers designating the panels or tables in which such age is shown.

In the form of my invention illustrated 5 in Figs. 1 to 4 my preferred means for simultaneously disclosing an index number or combination of such numbers with a permutation thereof comprises a circular disc J on which is inscribed or imprinted two 10 concentric rows of symbols, one of which comprises, as shown, index numbers or combinations thereof and the other of which comprises permutations of such index numbers or combinations of index numbers, and 15 such rows of numbers are preferably inverted to permit the exposition in upright position through openings on opposite sides of the axis about which said disc rotates of a pair of numbers comprising one or a 20 combination of the index numbers from one row which is paired with its permutation in the other row.

As illustrated in Figs. 1 to 4, an axle K is mounted at opposite ends in the facing 25 member A and a supporting strip L and the disc J is rotatably mounted on said axle K.

In the preferred form illustrated in Figs. 1 to 4, I provide means for rotating said disc intermittently to expose an index number or combination of numbers simultaneously with its paired and tabulated permutation for a predetermined time interval and then to move so as to expose the next 30 pair of such numbers and so on, and as illustrated, I connect to said disc, a disc or wheel M having spaced peripheral teeth N corresponding in number and spacing with the positioning of the numbers on the disc N and each of these teeth is engaged successively by a rotating, projecting actuating 35 arm O which moves in a circular path about an axis O' and engages, during each cycle of movement, a tooth on said disc N, only one of which projects into its path of movement at a time and therefore causes the two 40 discs to be moved for a distance equal to the space between the apices of the teeth and then releases the same and allows the disc to remain stationary for a considerable time interval while it is completing the balance of 45 its cycle and until it engages the succeeding tooth. Any suitable means may be employed to drive the arm and I have indicated a clock-mechanism P for this purpose.

50 In Figs. 5 and 6 I have shown a modified form of my invention in which A' is the facing member which is provided with exposure openings H'-I' and has imprinted thereon tables or discs similar to those shown in Fig. 1, and has also rotatably mounted at the rear thereof a disc J' provided with the two rows of index and permutation numbers respectively and which is substantially similar in all respects to the 55 disc J. As illustrated the disc rotates on

an eyelet K' which serves as an axle and a backing plate L', said eyelet K' being supported between the facing member A' and the backing member L' which is preferably provided with a depressed channel which 70 when the backing and facing members are connected together forms a housing for the disc to permit the rotation thereof at the back of the facing-member and enable the exposure through the openings H'-I' of 75 the numbers on the disc. As illustrated I provide a notch a in the edge of the facing and backing members so as to permit access of the fingers to teeth j formed on the periphery of the disc J'. 80

The operation of the device will be apparent from the above description.

Having described my invention, I claim:

1. In a puzzle device embodying, in combination, a plurality of tables each comprising a series of symbols and each table being individually identified with an index symbol, a relatively stationary member having a pair of exposure openings therethrough and a member movable at one side of said stationary member and having inscribed thereon two rows of symbols, one of which comprises symbols tabulated in said tables and the other of which comprises index symbols indicating the tables in which the tabulated symbols will be found, and means for successively exposing identifiable pairs of such symbols simultaneously. 90

2. In a puzzle device, embodying in combination, a plurality of tables, each comprising a series of numeric permutations, said tables being identified by numeric indices of the numeric permutations embodied in the tables, a relatively stationary member having a pair of exposure openings therethrough; a member movable at one side of said stationary member and having arranged thereon two rows of numbers, one of which corresponds with said numeric permutations and the other of which corresponds with the indices of such numeric permutations and indicates the tables in which the former numeric permutations will be found, and means for successively exposing identifiable pairs of such numeric permutations and indices simultaneously. 105

3. In a puzzle device embodying in combination, a plurality of tables, each comprising a series of tabulated symbols and each table being individually identified by means of an index symbol, a rotatable disc having arranged in two concentric rows thereon two sets of symbols comprising one set of tabulated symbols and another set of index symbols, said symbols being arranged in identifiable pairs. 120

4. In a puzzle device, embodying in combination, a plurality of tables, each comprising a series of tabulated symbols and each 125

- table being individually identified by means of an index symbol, a rotatable disc having arranged in two concentric rows thereon two sets of symbols comprising one set of tabulated symbols and another set of index symbols, said symbols being arranged in identifiable pairs and means for exposing said pair of identifiable symbols simultaneously while covering the balance of the disc. 5
- 10 5. In a puzzle device, embodying in combination, a relatively stationary member having a pair of exposure openings therethrough and a member movable at one side of said stationary member comprising a rotatable disc having arranged in two concentric rows thereon two sets of symbols comprising one set of tabulated symbols and another set of index symbols, said symbols being arranged in identifiable pairs, and means for exposing 15 through said exposure openings a pair of said identifiable symbols simultaneously. 20
6. In a puzzle device, embodying in combination, a relatively stationary member having a pair of exposure openings therethrough, a plurality of tables, each comprising a series of symbols and each table being individually identified with an index symbol all inscribed on said stationary member, a rotatable disc rotatably mounted at one 25 side of said stationary member having arranged in concentric rows thereon two rows of symbols comprising one set of tabulated symbols and another set of index symbols indicating the tables in which said former 30 tabulated symbols may be found, and means for exposing through said exposure openings a pair of said identifiable symbols simultaneously. 35
7. In a puzzle device, embodying in combination, a relatively stationary member having a pair of exposure openings therethrough, a plurality of tables, each comprising a series of numeric permutations, said tables being identified by numeric indices of 40 the said tabulated numeric permutations, a rotatable disc mounted to rotate at one side of said stationary member and having arranged thereon two concentric rows of numbers, one of which comprises numeric permutations corresponding to said tabulated permutations and the other of which comprises indices corresponding to said indices and indicating the tables in which the said numeric 45 permutations will be found, and being arranged in pairs identifiable by said tabulated permutations and indices, and means for exposing a pair of such numeric permutations and indices simultaneously through said 50 openings. 55
8. A puzzle device embodying, in combination, a facing member having inscribed thereon a plurality of tables, each comprising a series of symbols and each being individually identified by an index symbol, said 60 facing member also having cut therethrough two openings, a disc rotatable in the rear of said facing member having inscribed thereon two rows of symbols corresponding to the said tabulated symbols and index symbols respectively, and said symbols being arranged in identified pairs to cause an identified pair of symbols to be exposed simultaneously through the exposure openings in the facing member when the disc is rotated. 70
9. A puzzle device embodying, in combination, a facing member having inscribed thereon a plurality of tables, each comprising a series of symbols and each being individually identified by an index symbol, 75 said facing member also having cut therethrough two openings, a disc rotatable in the rear of said facing member having inscribed thereon two rows of symbols corresponding to the tabulated symbols and index symbols respectively, said symbols being arranged in identified pairs so as to cause an identified pair of symbols to be exposed simultaneously through the exposure openings in the facing member and mechanism for rotating said disc intermittently to successively expose such pairs of symbols. 80
10. A puzzle device embodying, in combination, a facing member having inscribed thereon a plurality of tables each comprising a series of symbols and each being individually identified by an index symbol, 85 said facing member also having cut therethrough two openings, a disc rotatable in the rear of said facing member having inscribed thereon two rows of symbols corresponding to the tabulated symbols and index symbols respectively, and said symbols being suitably spaced and arranged in identified pairs to cause an identified pair of symbols to be exposed simultaneously through the exposure openings in the facing member upon rotation of the disc, mechanism for rotating said disc intermittently to successively expose such pairs of symbols comprising a toothed wheel having teeth spaced to correspond with the spacing between the numbers on the disc and means for engaging each of said teeth independently to move an identified pair of symbols 90 into exposed position behind the exposure openings in the facing member. 100
11. A puzzle device embodying, in combination, a facing member having inscribed thereon a plurality of tables, each comprising a series of numeric permutations and each being individually identified by numeric indices, said facing member also having cut therethrough two openings, a disc rotatable in the rear of said facing member having inscribed thereon two rows of numbers corresponding to the tabulated permutations and indices respectively and said numeric permutations being suitably spaced 105 and arranged in identified pairs to cause an 110
- 120
- 125
- 130

identified pair of numeric permutations to be exposed simultaneously through the exposure openings in the facing member upon rotation of the disc, mechanism for rotating said disc intermittently to successively expose such pair of numeric permutations comprising a toothed wheel having teeth spaced to correspond with the spacing between the numbers on the disc and means for engaging each of said teeth independently to move an identified pair of numeric

permutations into exposed position behind the exposure openings in the facing member.

In witness whereof, I have signed my ¹⁵ name to the foregoing specification in the presence of two subscribing witnesses.
